UNITED STATES PATENT OFFICE.

JAMES P. NICHOLAS, OF STUTTGART, ARKANSAS.

PUMP.

1,199,594.

Specification of Letters Patent. Patented Sept. 26, 1916.

Application filed July 8, 1914. Serial No. 849,817.

To all whom it may concern:

Be it known that I, JAMES P. NICHOLAS, a citizen of the United States, residing at Stuttgart, in the county of Arkansas and State of Arkansas, have invented new and useful Improvements in Pumps, of which the following is a specification.

This invention relates to improvements in centrifugal pumps, especially adapted for operating in deep pits or deep wells such as irrigation wells, the invention consisting in the construction, combination and arrangement of devices hereinafter described and claimed.

15 One object of my invention is to provide an improved centrifugal pump of this kind in which the discharge pipes are free from obstruction and offer no internal resistance to the upward flow of water.

20 Another object is to effect improvements in the construction of the pump whereby the working parts may be readily kept lubricated under all conditions of operation and the lubricant may be readily supplied or 25 renewed while the pump is in operation.

Another object is to effect improvements 30 in the construction of the pump whereby the parts of the same may be readily assembled and disassembled to permit repairs to be readily made and afford easy access to 35 all of the parts.

Another object is to effect improvements 40 in the construction of the pump to permit the lubricating means and the driving shaft 45 to be raised and lowered without interfering with or having to pass through the discharge head or the discharge pipes.

Another object is to effect improvements 50 in the construction of the pump whereby the discharge pipes are rendered entirely independent of the driving shaft and its bearings and whereby the driving shaft and the discharge pipes may be made of any required length.

55 In the accompanying drawings: Figure 1 is a side elevation of the upper portion of a centrifugal pit pump constructed in accordance with my invention. Fig. 2 is a vertical sectional view of the same on a plane at right angles to Fig. 1. Fig. 3 is partly an elevation and partly a vertical sectional view of the lower or intermediate portions of the same. Fig. 4 is a detail plan view of the cap of the casing in which the centrifugal pistons operate. Fig. 5 is a detail side elevation of the same. Fig. 6 is a similar view

at right angles to Fig. 5. Fig. 7 is partly a plan of the head of the pump and partly a sectional view of the same on the plane indicated by the line *a*—*a* of Fig. 2. Fig. 8 is a detail sectional view of the same on the plane indicated by the line *b*—*b* of Fig. 7. Fig. 9 is a horizontal sectional view on the plane indicated by the line *c*—*c* of Fig. 3.

For the purposes of this specification, the well or pit casing in which the pump is arranged and operated is indicated at 1. A head 2 is arranged on the upper end of the casing 1 to close the latter. A casing 3 in which the centrifugal pistons 4 operate is arranged in the casing 1 at a suitable distance from the lower end thereof and the lower head 5 of the casing 3 has a central opening to which is connected the upper end of the intake pipe 6.

The vertical shaft 7 to which the centrifugal pistons are attached and which serves to rotate the said pistons has its upper end mounted in a bearing 8 in the upper side of a frame 9 which is mounted on the head 2. A pair of vertically arranged discharge pipes 10 are at opposite sides of and disconnected from the shaft 7, their lower ends communicating with the casing 3 and their upper ends discharging through the head 2. These discharge pipes are made in separable sections and the shaft 7 is also made in separable sections so that the pump may be lengthened by the addition of the pipe and shaft sections to any extent required by the depth of the pit or well in which the pump is to operate.

The cap 11 of the casing 3 is formed with a central depending boss 12 at the lower end of which is an annular flange 13 which is arranged above the upper centrifugal piston 4. The said cap also has a tubular portion 14 on its upper side centrally located and the said cap is formed with curved outlets 15 which project from its upper side, are centrifugally arranged with reference to the cap and each of which inclines in one direction, the intakes of these outlets being formed by vanes 16 which are formed with and connect the said cap and the flange 13. The outlets 15 are formed at their upper ends with circular flanges 17 which project outwardly therefrom and to which the flanges 18 at the lower ends of the lowermost discharge pipe sections 10 are secured by means of bolts 19, suitable packings being interposed at the joints between said

outlets 15 and said discharge pipe sections. The bore of the tubular portion 14 of the cap also extends through the cap, the flange 13 and the boss 12 and receives a bushing 20 5 of brass or other suitable metal or material and through which bushing the shaft 7 passes, the said bushing forming a bearing for said shaft and being provided at its upper end with a flange 21 which rests on 10 the upper end of the tubular portion 14 of the cap.

The shaft 7 comprises an upper section 22, a lower section 23 and any suitable number of intermediate sections 24 according to 15 the required length of the shaft. The opposing ends of the shaft sections are screw-threaded and are engaged by the threads of coupling sleeves 25. Hence, the shaft sections are detachably connected together.

20 The upper shaft section 22 passes through and revolves in a bushing 26 in a bearing 27 with which the lower plate 28 of the frame 9 is provided, and said upper shaft section also has a ball bearing 30 which is 25 mounted in a cup 31 formed on the bottom plate 28. A driving pulley 32 is secured on the upper shaft section by a key 33 and screw 34. The lower end of the hub of the pulley bears on a washer 34' which is above 30 the ball bearing and a collar 35 is screwed to the upper shaft section as at 36, bears on the upper end of the hub of the pulley and is held in place by a set screw 37.

Blocks 38 are arranged between the discharge pipe sections and are provided with central bores through which the driving shaft extends. These blocks are located at points substantially midway between the jointed ends of the discharge pipe sections, 35 are provided in their ends with recesses which receive and fit the opposing sides of the discharge pipe sections and are also provided at their corners with lugs 39. U-shaped bolts 40 engage the outer sides of 40 the discharge pipe sections and are secured to the lugs 39 by nuts 41 and bars 42, the arms of the U-bolts passing through the said lugs. Any other suitable means may be employed for securing the clamping or 45 U-bolts to the blocks. These blocks are secured together in pairs by the bars 42. Any other suitable means may be employed for connecting the blocks together within the scope of my invention. A lubricating 50 casing 43 incloses the major portion of the shaft 7. This casing comprises an upper tubular member 44 which connects the boss 27 of the plate 28 with the upper clamping block 38, and lower member 45 which connects the lower clamping block 38 with the tubular portion 14 of the cap 13 and intermediate members 46, one or more of which 55 connect the intermediate clamping blocks 38 together in pairs. The upper member 44 60 of the lubricating casing has a detachable

upper section 47 secured thereto by a screw coupling sleeve 48. The upper end of the section 47 is provided with a collar 49 screwed thereto and provided with an annular flange 50, this flange being engaged by the flange 51 of a coupling sleeve 52 which is screwed to the lower end of the boss or bearing 27.

70 The lower end of the lower member 45 is secured to the tubular member 14 of the cap 75 13 by a coupling sleeve 53 the upper end of said member 45 being screwed to a nipple 54 formed at the lower end of the lower clamping block 38. Each clamping block has a portion of its bore enlarged for the reception of a Babbitt or other suitable bearing sleeve 55 in which the shaft 7 revolves so that the said clamping blocks also form 80 bearings for the said shaft.

85 By the provision of the sectional discharge pipes, the clamps including the blocks and the U-bolts which secure the discharge pipes together and by the provision of bearings for the shaft in the said blocks, the shaft is kept in proper alignment and 90 the construction is rendered so rigid and strong as to be practically free from vibration. Moreover, the shaft and discharge pipes form continuous connections from the top of the pump down to the casing 3 and 95 the discharge pipes are rendered entirely independent of and are totally disconnected from the driving shaft and the bearings of the shaft are effectually prevented from being injured by sand or grit.

100 The lower end of the upper blocks 38 and the upper end of the lower block 38 are, respectively, provided with suitable packing boxes 56. Intermediate blocks, where they are employed in pumps that 105 operate in deep wells or pits will be connected together in pairs by intermediate members of the lubricating casing and will be provided on their opposing sides with threaded nipples for engagement by said intermediate members of the casing and at their outer ends with packing boxes.

110 A lubricating pipe 58 is connected to each member of the lubricating casing by a branch 59 and is provided at its upper end 115 with a reservoir 60 for lubricant and which is here shown as provided with a force feed arrangement which admits of hard lubricant being employed for the bearings of the shaft. Oil may, however, be employed as 120 a lubricant, if preferred. It will be noted that the various members of the lubricating casing will be kept full of lubricant which will be supplied to the bearings at all times and automatically so that the pump can be 125 driven at high speed and for a long period of time without danger of the bearings becoming dry and worn, and, moreover, lubricant may be supplied to the bearings from time to time and the pump kept in thor- 130

oughly lubricating condition indefinitely. A lubricating reservoir 61 is also provided which is connected by a pipe 62 to the cup 31 in which the ball bearing 30 of the shaft is 5 located.

The head 2 is formed with a pair of curved discharge arms 63 with which the upper ends of the discharge pipes 10 are connected, the said discharge arms 10 converging and being connected together by a union 64.

While I have herein shown and described a preferred embodiment of my invention, I would have it understood that changes may 15 be made in the form, proportion and construction of the several parts without departing from the spirit of my invention and within the scope of the appended claims.

I claim:—

20 1. A circular casing having a bottom provided with a central intake opening and also having a wall provided with a central contracted portion so that chambers are formed in the lower and upper portions of 25 said casing and a central passage is formed

between said chambers, spaced centrifugal pistons arranged one in each of said chambers, and a cap on the casing, having eccentrically located outlets and also having a flange spaced from the lower side thereof, 30 arranged in the upper chamber, bearing on said upper centrifugal piston and provided with vanes to deflect water into said outlets.

2. In a centrifugal pump, a centrifugal piston open on opposite sides, a casing for 35 said piston presenting a wall opposed to one open side of the piston, and a cap on the casing provided with eccentrically arranged outlets, said cap being provided with a flange, spaced therefrom, opposed to the 40 other open side of the piston and provided with vanes connected to the cap and arranged to deflect water into said outlets.

In testimony whereof I affix my signature in presence of two witnesses.

JAMES P. NICHOLAS.
